UNITED STATES PATENT OFFICE.

WILLIAM R. JEAVONS, OF CLEVELAND, OHIO.

DESIGN FOR A HYDROCARBON-BURNER.

SPECIFICATION forming part of Design No. 34,210, dated March 12, 1901.

Application filed January 11, 1901. Serial No. 42,926. Term of patent 7 years.

To all whom it may concern:

Be it known that I, WILLIAM R. JEAVONS, a citizen of the United States, residing at Cleveland, in the county of Cuyahoga and State of Ohio, have invented and produced a new and original Design for a Hydrocarbon-Burner, of which the following is a specification, reference being had to the accompanying drawing, forming part thereof, and illustrating the design in a single figure and in side elevation.

As thus shown, the design constitutes a new article of manufacture and sale, and the essential novelty of the design is comprised chiefly in its appearance as a whole and as it addresses itself to the eye when all the parts are viewed together; but there are also distinguishing and novel special features which make up the complete design. These consist,

first, in the shape or outline of the burner 2, 20 which is of a drum formation, and, secondly, in the features associated with the bottom of burner, the same disclosing a stem 4, which has the appearance of a support for the burner and also what resembles a tubular 25 handle 5, running off at an upward and outward inclination from the base of said stem past and above the bottom of the burner.

What I claim is—

The design for a hydrocarbon-burner, substantially as herein shown and described.

Witness my hand to the foregoing specification this 5th day of January, 1901.

WILLIAM R. JEAVONS.

Witnesses:

M. A. SHEEHAN,
R. B. MOSER.
